UNITED STATES PATENT OFFICE.

HERMAN MELLING, OF JACKSON, MICHIGAN, ASSIGNEE OF ONE-THIRD TO LEROY NORTHRUP AND ONE-THIRD TO GEORGE MELLING, OF JACKSON, MICHIGAN.

COMBINED ROUTER AND DIE-SINKER.

1,028,125.

Specification of Letters Patent.

Patented June 4, 1912.

Application filed June 29, 1911. Serial No. 635,960.

To all whom it may concern:

Be it known that I, HERMAN MELLING, a citizen of the United States of America, residing at Jackson, in the county of Jackson and State of Michigan, have invented certain new and useful Improvements in Combined Routers and Die-Sinkers; and I do hereby declare the following to be a full, clear, and exact description of the invention, such as will enable others skilled in the art to which it appertains to make and use the same.

My invention relates to improvements in combined routing and die sinking machines and its object is to provide a machine adapted to alternately operate a rotary routing tool and an oscillating die sinking tool; to provide improved means for operating the die sinking tool; to provide means for readily moving the routing tool into and out of operative position, and to provide the device with various new and useful features hereinafter more fully described and particularly pointed out in the claims, reference being had to the accompanying drawings, in which:

Figure 1 is a front elevation of a machine embodying my invention; Fig. 2 a side elevation of the same;—Fig. 3 a rear elevation of a portion of the same; Fig. 4 a plan view of the same with the bed omitted; Fig. 5 a detail of the rack and pinion mechanism of the die sinking tool shown partly in elevation and partly in section; Fig. 6 a front elevation in detail of the mechanism for the vertical and lateral movement of the die sinking tool in position for the back stroke; Fig. 7 the same in position for the cutting stroke; Fig. 8 a detail partially in plan and partially in horizontal section taken on the line 8—8 of Fig. 6; Fig. 9 a detail partially in vertical section showing the sliding attachment to the frame of the mechanism for operating the die sinking tool; Fig. 10 a detail in vertical section of a portion of the die sinking mechanism; and Fig. 11 a detail of the cam wheel.

Like numbers refer to like parts in all of the figures.

10 A represents the frame of the machine, B the bed to which the work is secured in the usual way, said bed having the usual vertical and horizontal movements to move the work in all directions relative to the tools.

1 is a horizontally disposed main driving shaft at the top of the frame. 2 a cone pulley driven by any suitable belt in the usual manner. 3 a vertical spindle carrying any suitable routing tool 4 at its lower end and journaled in arms 5^a mounted on a swinging member 5 hinged at one side to the frame as at 6 and secured in operative position by screws or other fastenings 7. This spindle is driven by miter gears 8, one on the driving shaft and one on the spindle, which gears are engaged when the spindle is in operative position. When the routing tool is out of use the fastenings 7 are removed and the spindle swung out of the way of the work as illustrated in Fig. 4.

9 is a housing for the die sinking tool having a semi-circular channel 9^b in which is slidably supported a segment shaped tool holder 10 in which is mounted a suitable die sinking tool 11 having substantially a circular head with cutting teeth on its sides and periphery, the axis of which tool is located in the axis of the segmental holder. The periphery of this holder is provided with a segmental pinion 17 engaged by a rack 36 to oscillate the holder in the casing. A channel 9^c is provided in the top of the casing in which the rack 36 is slidable.

12 is a vertically disposed dove-tailed way 85 fixed on the frame A on which way is a vertically movable slide 13 having a horizontal dove-tail way on which is slideable an arm 16 supporting the housing 9. The housing is thus mounted on the frame to move either vertically or horizontally by means of these ways and slide. The housing is supported and moved vertically by a toggle lever 14 pivoted to the housing at its lower end and to an arm 13 on the frame at its upper end.

17 is a rock shaft journaled in bearings on the frame and having a yoke 18 mounted on its forward end supporting the ends of an oscillating rod 19 on which is a slide 20 pivotally connected to a corresponding slide 21 mounted on a vertically disposed rod 22 on the arm 16, the slides 20 and 21 being vertically adjustable by means of a pin 23 in the slide 21 engaging any one of a series of holes in the arm 16. By adjusting the slides opposite the end of the rock shaft no horizontal movement of the housing is produced. By adjusting the slides above or below said shaft at greater or less distance,

more or less horizontal movement of the housing is produced on the forward stroke, if adjusted at one side of the shaft and on the back stroke if adjusted at the other side 5 of the shaft.

24 is an arm extending upward from the yoke 18 and 25 a connecting rod pivoted to the end of the arm at one end and to the middle joint of the toggle lever 14 at the 10 other end, whereby the housing is raised and lowered as the yoke is oscillated.

26 is an arm fixed on the rock shaft at one end and having a stud 27 at the other end engaging and traversing a groove 28 in 15 a cam wheel 29. This wheel is provided with a crank pin 30 on which is journaled a slide 31 adapted to traverse an arm 32 fixed on a rock shaft 33 whereby the rock shaft is given an oscillating and quick return move- 20 ment.

34 is an arm on the rock shaft and 35 a connecting rod which connects the arm 34 with the rack 36 operating the segmental holder 10. The cam wheel 29 is mounted 25 on a shaft 39 driven from the driving shaft 1 by means of a vertical shaft 38, bevel gears 40 and miter gears 41 as shown in Fig. 3.

In operation when the routing tool 4 is 30 in use the gear 41 on the shaft 39 is moved out of engagement with the gear 41 on the shaft 38 and thus the die sinking mechanism put out of action. When its work has been completed, the routing tool can then be 35 swung out of the way, the gears 41 reengaged, and the work adjusted by raising and moving the bed B to be properly engaged by the die sinking tool 11. On the forward stroke the upper end of the yoke 40 18 is oscillated toward the toggle lever whereby the same is operated to lower the tool into engagement with the work and at the same time the slides 20 and 21 being ad- 45 justed above the axis of the rock shaft 17 will adjust the tool laterally during the forward movement of the cutting stroke as in Fig. 7. On the return stroke the yoke 18 being oppositely oscillated will raise the tool and move it laterally out of engagement 50 with the work as illustrated in Fig. 6. If it is desired to operate the tool in reverse relation to the work all that is necessary is to adjust the slides 20 and 21 below the axis of the rock shaft 17. The side move- 55 ment of the tool will thus be reversed, thus engaging the opposite side of the tool with the work to cut in the opposite direction.

What I claim is:—

1. In combination, a vertically and hori- 60 zontally movable housing, a tool holder recipro- 65 ciprocable in the housing, a cutting tool carried by the holder adapted to cut both vertically and horizontally, means for recipro- cating the holder and means for simulta- 65 neously reciprocating the housing both ver-

tically and horizontally whereby the tool is engaged with the work both horizontally and vertically on its cutting or forward movement and disengaged therefrom on its return movement.

2. The combination of a frame, a slide vertically reciprocable on the frame, a housing horizontally reciprocable on the slide at right angles to the movement thereof, a tool holder recipro- 75 ciprocable in the housing, a cutting tool carried by the holder, means for reciprocating the holder in the housing and means for simultaneously reciprocating the housing on the slide and reciprocating the slide on the frame. 70

3. The combination of a die sinking tool, a holder for the same, a housing in which the holder oscillates in a segmental path, means for reciprocating the housing vertically, and means for oscillating the holder 80 in the housing.

4. The combination of a die sinking tool, a holder for the same, a housing in which the holder oscillates in a segmental path, means for oscillating the holder in the hous- 90 ing, and means for reciprocating the hous- ing horizontally.

5. The combination of a die sinking tool, a holder for the same, a housing in which the holder oscillates in a segmental path 95 and means for reciprocating the housing, both vertically and horizontally.

6. The combination of a die sinking tool, having a circular periphery provided with cutting teeth, a holder for said tool oscillat- 100 ing about the axis of the tool, means for os- cillating said holder, a housing carrying said holder and means for vertically recip- rocating the housing.

7. The combination of a die sinking tool, 105 having a circular periphery and provided with cutting teeth on its periphery and side, a holder for the same oscillating about the axis of the tool, a housing carrying said holder, means for oscillating the holder and 110 means for reciprocating the housing both vertically and horizontally.

8. The combination of a die sinking tool, having a circular periphery provided with cutting teeth, a segmental holder for said 115 tool, a segmental pinion on said holder, a housing having a segmental channel trav- 120 ersed by said holder, a rack slidable in the housing and engaging the pinion, means for reciprocating the rack, and means for vertically reciprocating the housing.

9. The combination of a frame, a die sink- 125 ing tool, a holder for the tool, a housing in which the holder oscillates in a segmental path, means for oscillating the holder, verti- 125 cal ways on the frame to guide the housing and means for reciprocating the housing on the ways.

10. The combination of a frame, vertical ways on the frame, a slide on the ways hav. 130

- ing horizontal ways, a housing mounted on the ways of the slide, a holder movable in a segmental path within the housing, a die sinking tool carried by the holder and means for reciprocating the housing both vertically and horizontally.
11. The combination of a frame, having an overhanging arm, a toggle lever pivoted to the arm at one end, a housing supported by the other end of the lever, ways to guide the housing, a die sinking tool carried by the housing, means for oscillating said tool, a rock shaft journaled on the frame and connected to the toggle lever to operate the same to raise and lower the housing.
12. The combination of a die sinking tool having a circular head provided with cutting teeth on its side, a holder for the tool movable in a segmental path about the axis 20 of the tool, a housing in which the holder is movable, ways on the frame on which the housing is guided both horizontally and vertically, a rock shaft on the frame, a toggle lever supporting the housing to move the same vertically, an arm connected to the rock shaft and to the toggle lever to operate the said lever to raise and lower the housing, said arm also being connected to the housing to reciprocate the same horizontally.
13. The combination of a frame, a housing mounted on the frame and adapted to move both vertically and horizontally, an arm on the frame above the housing, a toggle lever suspended from the arm and supporting the housing, a tool holder reciprocable in the housing, a die sinking tool carried by the holder, a rock shaft journaled on the frame, a yoke on the rock shaft, a rod connecting the yoke and toggle lever to move the housing vertically and adjustable means connecting the yoke and housing to move the housing horizontally.
14. The combination of a frame, a housing reciprocable both vertically and horizontally on the frame, a rock shaft connected to the housing to reciprocate the same, a tool holder oscillatable in the housing, a die sinking tool carried by the holder, a rack and pinion to oscillate the holder, a rotative cam wheel, an arm fixed on the rock shaft and operated by the cam wheel, a second rock shaft and arm fixed on the same, a slide on said arm, a crank pin in the wheel journaled in the slide, an arm on the second rock shaft and a rod connecting the arm and rack to reciprocate the rack.
15. The combination of a frame, a housing mounted on the frame and adapted to reciprocate both vertically and horizontally, a die sinking tool carried by the housing, means for oscillating said tool, a rock shaft journaled on the frame, means for oscillating the said shaft, a yoke on the rock shaft, an arm on the yoke, means for vertically reciprocating the housing operated by the arm, a pin in the yoke, a slide on the pin, a second pin on the housing and a second slide adjustable on the last named pin and pivotally connected to the first named slide.
16. The combination of a die sinking tool having a circular periphery, and provided with cutting teeth on both sides, a housing carrying said tool and mounted to reciprocate in the direction of the axis of the tool, means for oscillating said tool in the housing and means for reciprocating the housing, consisting of a rock shaft, a yoke on said shaft and means for connecting the yoke and housing, shiftable to opposite sides of the axis of the shaft and yoke.
17. The combination of a die sinking tool, having a circular periphery, and cutting teeth on its periphery and each side, a housing carrying said tool and mounted to reciprocate in the direction of the axis of said tool, means for oscillating said tool about its axis, a rock shaft, a yoke on the rock shaft and extending oppositely from the axis thereof, a pin mounted in the yoke, a slide on the pin adjustable at opposite sides of the axis of the shaft and means for connecting the slide to the housing to reciprocate the latter.

In testimony whereof I affix my signature in presence of two witnesses.

HERMAN MELLING.
